UNITED STATES PATENT OFFICE.

JOHN A. KLINE, OF READING, PENNSYLVANIA, ASSIGNOR TO THE READING STOVE WORKS, ORR, PAINTER & CO., OF SAME PLACE.

DESIGN FOR A HEATER.

SPECIFICATION forming part of Design No. 30,858, dated May 23, 1899.

Application filed April 29, 1899. Serial No. 715,062. Term of patent 7 years.

To all whom it may concern:

Be it known that I, JOHN A. KLINE, a citizen of the United States of America, and a resident of Reading, in the county of Berks and State of Pennsylvania, have invented a certain new and original Design for a Heater, of which the following is a specification.

The drawing is a perspective view of a heater, showing my new design.

As shown in the drawing, the leading features of my design relate to the front and base-ring of the heater and consist in the novel form and ornamentation of the several parts thereof, as follows:

The base-plate A is mainly of circular form with a squared front portion a, from which rises the ash-pit frame B, while the ornamented base-ring C conforms with the circular portion of the base-plate, as shown. The front D of the heater, which is of substantially rectangular shape, rises from the ash-pit and is framed by side columns E E and an overhanging top portion F and is provided with

a centrally-located rectangular fire-door G, having a bulging front g, with a central circular register g' and scrollwork ornamentation g². The face of the front between the columns E E is also provided with scrollwork ornamentation grouped, respectively, about a name plate or space d above the fire-door 25 and register-openings d' below the same. The rectangular ash-pit door H has similar ornamentation grouped about a draft-door h and covered grate-bar openings h', as has also the curved panel of the base-ring C, from 30 which projects at one point a vapor-pan box c. 35

What I claim is—

The design for a heater substantially as shown and described.

Signed by me, at Reading, Pennsylvania, 40 this 22d day of April, 1899.

JOHN A. KLINE.
